(57) **CLAIM**

The ornamental design for a bottle hook with wrench and cap opener, as shown.

DESCRIPTION

FIG. 1 is a top and front perspective view of a bottle hook with wrench and cap opener, in accordance with my new design; FIG. 2 is a bottom plan view of the bottle hook with wrench and cap opener shown in FIG. 1;

FIG. 3 is a top plan view of the bottle hook with wrench and cap opener shown in FIG. 1;

FIG. 4 is a side elevational view of the bottle hook with wrench and cap opener, taken from the right side of FIG. 3; FIG. 5 is a side elevational view of the bottle hook with wrench and cap opener, taken from the left side of FIG. 3; FIG. 6 is a front elevational view of the bottle hook with wrench and cap opener shown in FIG. 1;

FIG. 7 is a rear elevational view of the bottle hook with wrench and cap opener shown in FIG. 1; and,

FIG. 8 is a top perspective view of the bottle hook with wrench and cap opener shown in FIG. 1.

The broken line representation of a bottle and bottle cap in FIG. 8 is shown for illustrative purposes only, and forms no part of the claimed design.
